Patent expires February 8, 1966

6 Claims. (Cl. 315—6)

1

This invention relates to the control of thermal expansion in electromagnetic systems, particularly as regards the operating frequency of electron discharge devices intended for the generation of hyper-frequency electromagnetic waves.

It is an object of this invention to provide means whereby the resonant frequency of a system including an electromagnetic resonator may be made substantially independent of temperature changes.

It is a further object of the invention to provide means whereby the operating frequency of an electron discharge device which includes an electromagnetic resonator as part of the construction thereof may be made substantially independent of temperature variations.

Yet another object of the invention is to provide means whereby the operating frequency of such electron discharge device may be controlled by deliberately altering the temperature of part or the whole of the structure of the same preferably by electronic means incorporated within the device.

In order to show the general nature of the problem and of its solution we may consider a particular example. In Figure 1 there is illustrated diagrammatically a length of coaxial line short-circuited at one end and having an internal projection 1 on the outer conductor 2 so as to form in conjunction with the central conductor 3 a small condenser shunting the line. In practice it is common for such condenser to comprise a screw threaded into the outer wall. Although a short circuited line is then dealt with, the result is equally applicable to an open circuited line.

Figure 2 is a diagrammatic view looking down the open end of the line.

For the short circuited case the resonant frequency of the combination of line and condenser is given by

$$\omega C_0 - \frac{1}{Z_0} \cot \frac{\omega l_0}{v} = 0 \quad (1)$$

in which C_0 is the capacity of the condenser, Z_0 the surge impedance of the line, l_0 the length of the line, v the wave propagation velocity therein and ω the pulsatance, all quantities being taken at some arbitrary temperature T_0 . If now the

2

temperature changes by an infinitesimal amount dT there will result a frequency shift determined by

$$\frac{d\omega}{\omega} = \frac{2\eta \frac{dl}{\lambda_0} (1 + \omega_0^2 Z_0^2 C_0^2) + \omega_0 Z_0 dC + \omega_0 C_0 dZ_0}{2\eta \frac{l_0}{\lambda_0} (1 + \omega_0^2 Z_0^2 C_0^2) + \omega_0 Z_0 C_0} \quad (2)$$

in which λ_0 is the wavelength corresponding to ω_0 .

Now the capacity C_0 is proportional to the area of the opposing plates of the condenser and inversely proportional to their separation. While Z_0 is proportional to $\log$

15

 $\frac{r_2}{r_1}$

r_2 and r_1 being the radii of outer and inner conductor respectively. Hence, if all conductors of the resonator system are of the same material and the system is heated uniformly we shall have

$$dC = \alpha C_0 dT \quad (3)$$

α being the coefficient of linear expansion of the material. Hence in this case

$$\frac{d\omega}{\omega} = \alpha dT \quad (3)$$

Equation 3 is quite general whatever the shape of the resonator.

From Equation 2 it is seen that it would be possible to compensate for thermal effects if dC or dZ_0 could be made negative.

If now the central conductor were to be made of material having a smaller coefficient of expansion than that of the material of the outer conductor the separation of the plates of the condenser would be greater than would be the case for a resonator system composed throughout of the same material, and by the suitable choice of these materials and of the dimensions of its parts it is possible to arrange that dC shall be negative and that the numerator on the right-hand side of Equation 2 be zero. In this case, however, Z_0 would increase.

An alternative method would be to keep the materials of inner and outer conductor the same but to arrange that a part of the projection 1 (Figure 1) be of material having a smaller coefficient of expansion, so that the separation of the condenser plates results in a decrease of

capacity and at the same time the surge impedance of the line is unaltered.

Various other similar ways of securing a decrease in the capacity, surge impedance, or both, of the resonator system could well be devised in conformity with the principles of the present invention according to which there is provided an electromagnetic resonator in which changes of temperature are compensated for by including materials of different thermal expansions in the construction of said resonator and suitably proportioning the dimensions thereof.

In electron discharge devices for the generation of very high frequencies the construction usually includes an electromagnetic resonator within the tube envelope.

It is a common feature of most such devices that there is provided an electro-magnetic resonator system in which an electro-magnetic field is set up, and an electron beam which passes through, or across one or more gaps of the resonator system, and interacts with the electro-magnetic field. The operating frequency approximates to the natural frequency of the resonator system considered purely as an electro-magnetic resonator, while the departure of the operating frequency from the natural resonator frequency is dependent in general upon three features: external circuit loading, reactive loading due to interaction between the electro-magnetic field and the electron beam and a capacitative loading due to the gap or gaps across which the electron beam is projected.

During operation energy from the electrode polarising supplies is inevitably dissipated as heat and the structure of the device will normally be subject to appreciable temperature rise resulting in change of dimensions and consequent frequency drift. For example, if a copper resonant circuit of any shape designed for use at a frequency of 3,000 mc./s. were to suffer a temperature change of 100° C., a frequency change of the order of 5 mc./s. would result. Fractional changes in power input to the system will lead to corresponding fractional changes of frequency which may well be serious if the oscillator is being used, for example, as beating oscillator in a narrow-band receiver.

The effect of temperature rise is to cause a change in the dimensions of the resonator as such, thereby tending to increase the wave length, but the change of gap dimensions is such as to increase the separation between opposite faces with a consequent tendency to reduce the capacitative loading, although this is usually more than offset by the increase of the effective area of the plates of the condenser formed by the gap.

If now means could be devised for increasing the gap dimensions in such manner that the reduction of capacity thereby more than offsets the increase of capacity due to increase of surface area, together with increase in the natural wave-length of the resonator system as such, it would be possible not only to offset any frequency drift due to temperature rise, but also by controlling the temperature to change the operating frequency at will. Such a solution may be obtained by utilising materials of different rates of thermal expansion in the construction of the electron discharge device.

In accordance with this aspect of the invention there is provided an electron discharge device having means for projecting a beam of electrons through an electro-magnetic resonator system

associated with said field in which materials having different coefficients of thermal expansion are used in the construction of said resonator system so that the relative expansion of parts of said resonator system are so controlled as to maintain the operating frequency substantially constant in spite of thermal variations in said system.

According to another aspect of this invention there is provided an electron discharge device, having means for projecting a beam of electrons through an electromagnetic field, thereby exciting an electromagnetic resonator system associated with said field, in which materials having different coefficients of thermal expansion are used in the construction of said resonator system so that the relative expansions of parts of said resonating system are so controlled as to vary the operating frequency in sympathy with the potential difference between electrodes controlling a beam of electrons which heats one or more parts of said resonating system by impinging thereon.

Other aspects of the invention and the manner in which they are to be performed will be more clearly understood from a consideration of the following description and further drawings, in which:

Figure 3 is a diagrammatic representation of a longitudinal section through the resonator system of a typical velocity modulation tube.

Figure 4 is a section through the line 4—4 of Figure 3.

Figures 5 and 6 are similar to Figures 3 and 4 respectively, but show preferred means for achieving one of the objects of this invention while Figure 7, corresponding to Figures 3 and 5, shows alternative means for carrying out this object.

Figure 8 is an elevational view in part section of a high frequency electron discharge device in accordance with the invention in which thermal frequency drift has been eliminated.

Figure 9 is a section through the line 9—9 of Figure 8.

Figures 10 and 11 are diagrammatic views of vertical and horizontal sections respectively of a device according to the invention in which predetermined change of frequency is accomplished by utilisation of the thermal effect.

Referring now to Figures 3 and 4 which are representative of the coaxial type of resonator systems, 4 is the outer conductor carrying fins 5 which extend inwardly to reduce high frequency leakage; 6 is the inner conductor carrying fins which enclose the oscillator "drift" space and 8 is an antenna which can be coupled to an external and tunable cavity circuit of the well known "wave-guide" type.

When such a system is heated by the electron beam used in operation, expansion of all the parts will take place. If this expansion were uniform the proportional extension of the gaps 9 would be equal to that of the length and diameter of the whole structure and, by the laws of similarity, the relative increase of wavelength would be numerically the same. It will be noted, however, that the extension of the gaps will reduce the capacity loading introduced by the fins and hence reduce the wavelength were it not more than balanced by the effect of the increase of both fin thicknesses and fin length along the axis of the tube.

If, then, the relative expansion of the gaps could be increased, the increase of wavelength

consequent upon heating could be reduced or eliminated.

In Figures 5 and 6 is illustrated a means by which this may be done. A slot 10 is cut in each fin 7 along the length of the centre line to a sufficient length for a small degree of relative movement of the two sides to be possible without the introduction of excessive forces. The two sides are then joined in the middle by strips 11 of material, for example tungsten, of lower coefficient of expansion than the rest. It can be readily seen that the gaps 9 will then increase more rapidly than proportionally to the increase of length of the system and this will lead to compensation of the tendency for the frequency to change if the dimensions of the system are properly chosen.

The possibility of complete elimination of the frequency change by the system shown in Figure 5 depends on the relative dimensions along the direction of electron flow of the gaps 9 and the fins 5, the proportional change of the gaps 9 of course being greatest when their original length is least.

If the compensation obtainable is inadequate, owing to the fact that the lengths of the gaps are large, the modification shown in Figure 7 may be used. Here the low-expansion-coefficient strips 12 are arranged diagonally so that when the centre conductor expands longitudinally, by a form of "lazy tongs" effect, the effective width of the inner conductor may actually be reduced by heating.

In either case, when the expansion coefficients of the materials available are known, it is easy to calculate the correct lengths and points for fixing of the strips 11 of Figure 5 or 12 of Figure 7.

It may further be noted that the slot 10 of Figure 5 does not harm the operation of the oscillator as the lines of current flow in a coaxial system will be parallel to this slot.

In Figure 8 is illustrated a practical assembly of a velocity modulation device of the above described type. The details already mentioned are indicated by like reference numerals. The complete device comprises a glass envelope suitably based with pins 13 for connection to external supply circuits. 14 is an annular metallic disc bonded to the envelope 15 and to a glass cap 16 surrounding the antenna 8 and provided with an exhaust tabulation 17. The resonator tube 4 is fixed to this annular disc 14, which also provides a convenient means for mounting the assembled tube onto the wall of a wave guide so that the antenna 8 projects inside the cavity. The remaining electrodes are mounted on support wires 18 which connect with the pins 13. In addition to the resonator system already described, the electrode system comprises an indirectly heated cathode 19 behind which is mounted a screen 20; control grid 21 and screen grid 22 control and screen grids assist in focussing a ribbon-shaped beam of electrons which is projected through the resonator system onto an anode 23 at the far end of the gap system. The primary electron focussing means is a magnetic field provided by suitably placed field coils external to the tube structure.

An electron discharge device as described above would be compensated for temperature changes. It would not be a matter of great difficulty to provide such a device with a second controlled electron beam designed to heat the resonator system either directly or indirectly by means of electron bombardment. The cathode could

well be enlarged and independent focussing means and control electrodes added to form the said second beam. The temperature of the resonator system, and by proper proportioning of the parts thereof, hence the oscillation frequency, could be adjusted by variation of polarising potentials applied to the control electrodes of said second electron beam. The further modification about to be described, however, is to be preferred, as thereby a greater range of frequency variation can be obtained for the same change of said polarising potentials.

In Figures 10 and 11 part of a modified form of resonator system is illustrated diagrammatically. Instead of a slit in the central conductor, the drift tube 24 is made in two halves, and instead of the central conductor 4' (Figure 8) of the lower part of the coaxial line resonator system, we have two separate supports 25 performing the same electrical function. The two portions 24 of the drift tube are arranged to overlap, leaving small gaps 26 between them. At the very high frequencies for which these tubes are designed the capacity across the gaps 26 is sufficiently large to present negligible impedance to alternating current at the operating frequency. Furthermore, the characteristic impedance of a resonator system in which the central conductor takes the form of a pair of ribbon shaped members differs but little from that of the conventional coaxial line, so that the electrical design of the resonator system is not fundamentally altered by the modification. Each of the supports 25 is constructed of two lengths of bimetallic strips end-to-end, but reversed in their direction of bend. When the bimetallic strips are heated the two halves bend in opposite directions so that the associated half of the drift tube does not depart sensibly from the vertical but is moved bodily towards the wall of the resonator tube thus decreasing the gap 23. The bimetallic supports are arranged to be heated by a second electron beam in the manner previously described. Arrangements for this are not shown in the drawings, but in one particular application it is arranged that the support nearer the cathode is bombarded by a portion of said second beam and has holes therein arranged to allow a further portion of this beam to impinge on the other bimetallic support. In this manner the temperature of the bimetallic strips, and hence the working gap dimensions and the oscillation frequency of the device, is controlled in sympathy with the potential variation applied to control electrodes of the aforementioned second electron beam.

What is claimed is:

1. In a cavity resonator for a velocity modulation tube, a pair of conductors disposed in coaxial relation to form a resonant space, said conductors having aligned apertures therethrough to provide a path for flow of electrons, the portions of said conductors defining said apertures forming narrow gaps between said path and said resonant space, the inner one of said conductors having two relatively movable parts to control the width of said gaps, and means connected to said parts having a given coefficient of expansion different from the coefficient of expansion of the material of said parts to control in response to changes in temperature the relative movement of said parts.
2. In a cavity resonator according to claim 1, wherein said means includes an element having said coefficient of expansion interconnecting said parts.
3. In a cavity resonator according to claim 1, wherein said means includes a pair of elements

having said coefficient expansion interconnecting said parts at spaced points.

4. In a cavity resonator according to claim 3, wherein said elements are disposed in parallel spaced relation.

5. In a cavity resonator according to claim 3, wherein said elements are disposed cross-wise of each other.

6. In a cavity resonator according to claim 1, wherein said means includes a bimetallic ele- 10
